Primary Examiner — Selina Sikder(74) *Attorney, Agent, or Firm* — Maier & Maier, PLLC(57) **CLAIM**

The ornamental design for an operating device, as shown and described.

DESCRIPTION

FIG. 1 is a perspective view from the front and top of an operating device showing my new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines are for illustrative purpose only and form no part the claimed design.
